TIMING DEVICE

Edward S. Glover, Bristol, Tenn.

Application February 25, 1937, Serial No. 127,790

5 Claims. (Cl. 161—17)

This invention relates to timing devices and particularly to timers for games played in timed periods.

One important object of the invention is to provide a novel timer for this purpose wherein means are provided for indicating each period of the play and other means are provided for indicating the playing time remaining in any period.

10 A second important object of the invention is to provide a novel construction of such a timer wherein the return of the time indicator to its starting position after completion of one period of play will automatically effect operation of the 15 period indicator and shift the said period indicator from a position indicating one period to a position indicating the next successive period.

A third important object of the invention is to provide a novel construction of such a timer 20 wherein the construction embodies an audible signal effectively operated by arrival of the time indicating device upon completion of each playing period.

A fourth important object of the invention is to provide a novel return mechanism for the time 25 indicating device of such a timer.

A fifth important object of the invention is to provide a timer of this class with an electric motor for the driving mechanism of such a timer, the motor having a circuit which may be opened to render the timer inoperative during 30 intermissions in the play.

With the above and other objects in view, the invention consists in general of certain novel details of construction and combination of parts 35 hereinafter fully described, illustrated in the accompanying drawings, and particularly pointed out in the claims.

In the accompanying drawings, like characters 40 of reference indicate like parts in the several views, and:

Figure 1 is a front elevation of the invention,

Figure 2 is an enlarged section on the line 2—2 of Figure 1.

45 Figure 3 is a section on the line 3—3 of Figure 2, the section being on a smaller scale than Figure 2,

Figure 4 is a section on the line 4—4 of Figure 3,

50 Figure 5 is an enlarged section on the line 5—5 of Figure 2,

Figure 6 is a diagram showing certain electrical instrumentalities and their wiring connections as used in this invention, and

55 Figure 7 is a detail view illustrating a portion of the track bar 26.

In the embodiment of the invention as herein illustrated the device has been shown for use in connection with a game having four periods of play such as are called "quarters" in basket ball,

each period being of fifteen minutes in duration. It will be plain, from what follows, that devices embodying the same principles of construction may be arranged for other numbers of playing periods and other durations of such periods.

5

As here shown there is provided a casing having a bottom 10, front wall 11, rear wall 12, and end walls 13. Mounted on the rear wall adjacent one end of the casing is a bracket 14 whereon is secured a motor 15 having a shaft 16. On the 10 shaft 16 is fixed a worm 17 which meshes with a worm-wheel 18. Adjacent each end wall 13 is a plate 19 and in these plates is journaled the end portions of a shaft 20 having the worm-wheel 18 fixed thereon. This shaft 20 is threaded 15 to form a screw for purposes presently set forth. Also journaled in the plates 19 is a second screw 21 which projects at one end through an end wall 13 and the projecting end is provided with a knurled screw-head 22 by which the screw 21 20 may be turned. A sleeve 23 is slidably mounted on the screw 21 so that the sleeve may slide smoothly along the screw and may also turn thereon. The screw 21 is spaced close to the rear wall 12 while the screw 20 is spaced considerably further forward, being slightly nearer 25 the front wall 11 than the rear wall 12. Projecting forwardly from the sleeve 23 is an arm 24 which extends over the screw 21 and is provided on its under side with a half-nut 25 engageable with the screw 20 to cause the arm 24 and sleeve 23 to traverse the rear screw 21 as the screw 20 is rotated. By rocking the arm 24 upwardly the half-nut 25 is freed from the screw 20, thus permitting the sleeve and arm to 30 freely traverse the screw 21.

35

Means are provided to lift the half-nut from the screw 20 at one end of its movement along the screw and to hold it elevated during its return movement. To this end a track bar 26 is 40 fixed within the casing to extend along the front part thereof close to the front wall 11. Adjacent one end the track bar is provided with a slot 27. Fixed to the floor or bottom 10 of the casing is a leaf spring 28 which inclines upwardly and laterally in the direction of movement of the bar under the influence of the screw 20. The free end of the spring extends up into the slot 27 and terminates about flush with the upper face of the track bar 26. Projecting forwardly from the arm 24 is a nose 29 and the spring 28 is positioned in the path of this nose so that, as the arm 24 moves under the influence of the screw 20, this nose engages the spring 28 and travels upwardly thereon through the slot 27. It is to be observed 45 that the upper face of the bar 26, at one side of this slot, is bevelled as at 30.

40

Mounted on the rear wall 12 is a post 31 whereon is revolvably mounted a drum 32. Within this drum there is provided a spirally wound 50

50

55

60

spring 33 the inner end of which is anchored to the post 31 while its outer end is fixed to a pin 34 carried by the drum. Wound on the drum 32 is a cable 35 which has its free end connected by a clip 36 to the arm 24. Thus, when the arm is moved by the screw 20 the cable unwinds from the drum and the spring 33 is wound up. Upon the nose 29 engaging the spring arm 28 the arm 24 is tilted until, just as the nose rises through the slot 27, into position above the track bar 26, the half-nut 25 releases from the screw 20 and the drum, under action of the spring 33, rewinds the cable 35 and thus pulls the arm along the screw 21 towards its starting position. The track bar 26, in addition to the slot 27, is provided with other slots 37 spaced along its extent at preferably equal distances. Each of the slots is inclined to the upper face so that, as the nose 29, moves along the track bar under the influence of the spring 33, it will skip over these slots without dropping therethrough unless its motion be checked at some one of the slots. In order to effect checking of the return movement of the arm 24 by the spring 33 there is provided a T slot 39 extending along the inner face of the back or rear wall 12. On the screw 21 is mounted a nut 40 having a head 41 which slidably fits the slot 39. By turning the head 22 the screw 21 is rotated and the nut 40 will travel along the screw and may thus be positioned at such a point in the path of the sleeve 23 that the arm 24 will be in position for its nose 29 to drop through a selected slot 37. This, of course, permits re-engagement of the half-nut 25 with the screw 20. The action of these parts, during operation of the motor, will be a movement of the arm 24 to the left (in the present construction) under the influence of the screw 20, lifting of the arm 24 by the spring arm 28 until the half-nut 25 is disengaged from the screw 20 and the nose 29 is positioned to ride on the track bar 26, return of the arm 24 by the spring 33 until the sleeve 23 strikes the adjustable stop nut 40, and dropping of the nose 29 through a slot 37 and reengagement of the half-nut 25 with the screw 20.

In the front wall 11 is provided a longitudinal slot 42 above which is a graduated scale 43 the divisions of which indicate time periods and fractions thereof, the scale indicating minutes and quarters of minutes. Attached to the free end of the arm 24 is a pointer or index 44 which projects through the slot 42 and traverses the scale 43 from right to left while the scale divisions increase in numbering from left to right. By this means the index 44 directly indicates the remaining time for play in the period being played and not the elapsed time of play. Thus, Figure 1 shows that about 13 1/8 minutes are left for play, from a 15 minute period. Since the rotation of the screw must be at a uniform speed at all times, it is preferred that the motor be a synchronous motor although any desired means may be employed to insure uniformity in the R. P. M. of the motor. It will also be noted that the under face of the bar 26 is beveled at the sides of the slots 37 opposite the beveled portions 38, as shown at 45, to prevent catching of the nose 29 as the arm 24 is advanced by the screw 20.

Fixed to the floor or bottom 10 centrally of the length of the casing is a bracket 46 having a bearing 47 formed on its upper end. Journalled in the bearing 47 is a shaft 48 on the forward end of which is fixed a spider 49 supporting a period indicating disk 50 having period indicia 51 shown on its forward face so that they may

be successively observed through a sight window 52 in the front wall 11. Extending radially from the disk 50 are arms 53 spaced equally about the disk and equaling in number to the number of period indicia 51. These arms are so positioned that one arm will always lie in the path of the inner portion of the index 44 on the arm 24 on its raised return movement and will be engaged by said index 44 shortly after the start on such return movement to cause a partial rotation of the disc 50. As here shown there is provision for four playing periods or quarters. Obviously other than a full return movement of the arm 24 will not necessarily fail to effect the proper rotation of the disk 50 to display the period number in advance of that previously observable through the window 52. In order that the disk 50 may be caused to properly rotate through the desired arc and be held against accidental movement after being turned to display the proper character through the window 52, mechanism is provided such as is illustrated in detail in Figure 5. This mechanism includes a cam 54 having a series of low spots 55 and a series of high spots 56 alternating with the low spots and equal in number to the arms 53. A bracket 57 is fixed to the rear wall 12 and a lever 58 has one end pivoted to this bracket. On the remaining end of this lever is revolvably mounted a roller 59 which rests on the cam 53. A tension spring 60 has one end fixed to the lever 58 and extends downwardly therefrom to have its lower end fixed to a post 61 carried by the rear wall 12. By reason of this arrangement the cam 54 will, as its rotation starts upon the return movement of the arm 24, cause the lever 58 to lift until the roller 59 rises over the adjacent high spot 56 whereupon the spring 60 will pull the lever down until the roller 59 rests on the succeeding low spot 55, thus forcing the disc around and holding the disk 50 until it is again moved by the index 44. It will be obvious that the cam may be properly designed to effect this purpose no matter how many periods are to be indicated.

In order to provide signalling means for the ends of periods there is mounted on the floor or bottom 10 a circuit closer 62, comprising a bracket 62a to which is secured a spring arm 63 carrying an insulating block 64 provided with spaced terminals 65. One of these terminals constitutes a fixed contact while the other terminal carries a spring contact arm 66 which extends across the fixed contact and into the path of a lug 24a on the arm 24 at the end of the advancing movement of the latter, the circuit closer thus formed being normally open. An adjusting screw 67 is screwed through the bracket 62 and engages the spring arm 64 to flex the latter and thus adjust the position of the spring contact 66 with relation to the termination of the advancing movement of the arm 24. A gong or bell 78 is mounted on one end of the casing. As shown in Figure 6 a current source 69 such as a pair of house wires has the motor 15 and gong 68 connected in multiple to one side of the current source by wiring 70. The motor and gong are also connected in multiple to the other side of the current source by wiring 71, the circuit closer 62 is in series with the gong. A lamp 72 for illuminating the scale 43 and the indicia 51, also to indicate whether or not the device is in operation, is connected in multiple with the motor.

In order that the motor 15 may be automatically stopped at the end of a period, also in order that it may be stopped and started at will, by

the time-keeper, the wiring 71 passes through switches 73 and 74, both of which are of the three-way snap type. The switch 73 is of the rotary type and being attached to the rear wall 12 with its operating means connected to the adjacent end of the shaft 48 so as to be operated thereby each time said shaft makes a partial rotation, at the end of a playing period, which operation breaks the circuit to the motor and the other electrically operated elements. The switch 74 is positioned at any convenient point. By means of this, the time-keeper may control the current through the wiring 71 so as to stop and start the apparatus during the course of play, as for taking out time. Also by means of this switch, the apparatus may be started at the beginning of a period of play by snapping it to cause the current to flow through either the wire 71a or 71b, according to the position the switch 73 will have assumed at the end of the preceding period of play. In Figure 6, the switches 73 and 74 are set for operating the device with the current passing through the wire 71b.

From the foregoing, it will be seen that the index 44 slowly traverses the scale 43 during each playing period until it reaches its left extremity of travel, at which time the gong rings and the index 44 then returns rapidly to its starting point, carried by the arm 24. As the index returns, it imparts a partial rotation to the disk 50 so as to shift another period indication into position for observation through the window 52 and so as to operate the switch 73, through the medium of the shaft 48, to stop the operation of the entire device.

What is claimed is:

1. In a timer for games played in a plurality of periods of definite time duration, time indicating means including an index and a time scale traversed thereby, a motor, a feed screw extending parallel to said scale and driven by said motor, a support extending parallel to said feed screw, an arm for said index carried by said support and slidably and rockingly mounted thereon, said arm extending across said feed screw and provided with threads engaging said feed screw, a guide rail provided with a plurality of slots two of which are at the respective ends of the path of the index, said arm moving beneath said guide rail during engagement with the feed screw, camming means for raising the arm through the slot at one end of the path of the index to disengage it from the screw and to rest it on said guide rail, and means for returning the index and arm to the other end of the path whereby to permit the arm to drop through the slot at the last mentioned end and to engage the feed screw.

2. In a timer for games played in a plurality of periods of definite time duration, time indicating means including an index and a time scale traversed thereby, a motor, a feed screw extending parallel to said scale and driven by said motor, a support extending parallel to said feed screw, an arm for said index carried by said support and slidably and rockingly mounted thereon, said arm extending across said feed screw and provided with threads engaging said feed screw, a guide rail provided with a plurality of slots two of which are at the respective ends

of the path of the index, said arm moving beneath said guide rail during engagement with the feed screw, camming means for raising the arm through the slot at one end of the path of the index to disengage it from the screw and to rest it on said guide rail, means for returning the index and arm to the other end of the path whereby to permit the arm to drop through the slot at the last mentioned end and to engage the feed screw, and means for adjusting the length of the path traversed by said index.

3. In a timer for games played in a plurality of periods of definite time duration, time indicating means including an index and a time scale traversed thereby, a motor, a feed screw extending parallel to said scale and driven by said motor, a stop adjusting screw extending parallel to said feed screw, an arm for said index carried by said stop adjusting screw and slidably and rockingly mounted thereon, said arm extending across said feed screw and provided with threads engaging said feed screw, means for engaging and disengaging the threads at each end of the path of said index, means for returning the index to initial position upon disengagement of the threads from the feed screw, a non-revolvable nut on the stop adjusting screw forming a stop for said arm, and means to rotate said stop adjusting screw.

4. In a timer for games played in a plurality of periods of definite time duration, time indicating means including an index and a time scale traversed thereby, a motor, a feed screw extending parallel to said scale and driven by said motor, a stop adjusting screw extending parallel to said feed screw, an arm for said index carried by said stop adjusting screw and slidably and rockingly mounted thereon, said arm extending across said feed screw and provided with threads engaging said feed screw, a guide rail provided with a plurality of slots two of which are at the respective ends of the path of the index, said arm moving beneath said guide rail during engagement with the feed screw, camming means for raising the arm through the slot at one end of the path of the index to disengage it from the screw and to rest it on said guide rail, means for returning the index and arm to the other end of the path whereby to permit the arm to drop through the slot at the last mentioned end and to engage the feed screw, a non-revolvable nut on the stop adjusting screw forming a stop for said arm, and means to rotate said stop adjusting screw.

5. In a timer for games played in a plurality of periods of definite time duration, time indicating means including an index and a time scale traversed thereby, motor driven means for moving the index in one direction over the scale from a starting point, spring means for returning the index to the starting point, means for shifting the index between control by the motor driven means and control by the spring means at the ends of the path of movement of the index over the scale, a movable play period indicator shifted from one position to another by the return movement of said index, and means operated by the movement of the play period indicator for stopping the motor.
